ROLL HANDLING DEVICE

Carl E. Moore, Gary, Ind.

Application January 15, 1938, Serial No. 185,215

2 Claims. (Cl. 294—67)

This invention relates to rolling mill roll handling devices of the type comprising a beam having a roll neck socket at one end and a counterpoise at its other end. The counterpoise is for the purpose of balancing a roll whose neck is engaged by the socket on the other end of the beam, the latter being suspended by a crane or the like during the process. To effect proper balancing the beam must be suspended from different points, depending on whether the device is handling a roll. The determination of the proper suspension points and the shifting from one point to another during engagement and disengagement of a roll neck are very ticklish operations, and the primary object of the present inventor is to provide a remedy for this situation.

A specific example of a roll handling device embodying the principles of the invention is illustrated by the accompanying drawings, in which:

20 Figure 1 is a top plan of the device;
Figure 2 is a side elevation; and

Figure 3 is a cross-section taken from the line III—III in Figure 1.

More specifically, the device includes a beam 1 provided with a suspension plate 2 having a crane hook opening 3. One end of this beam 1 carries a roll neck socket 4 while its other end carries counterpoises 5.

One characterizing feature of the device is the 30 two counterpoises 5 and the mounting of these counterpoises on the end of the beam 1 by way of vertical shafts 6 journaled through anti-friction bearing 7 by arms 8 extending horizontally from the end of the beam 1. By means of this arrangement the counterpoises 5 may be swung horizontally to the position shown by broken lines, suitable bearings 9 taking the downward thrust. By reason of this arrangement the center of gravity of the device may be kept directly 40 beneath the crane hook opening 3 at all times regardless of whether the socket 4 is engaging a roll neck.

The counterpoises 5 are fixed to the shafts 6 so as to turn the same while a gear train 10, extending over the top of the device and interconnecting these shafts 6, serves to compel the two counterpoises to swing in opposite directions in synchronism, whereby to prevent canting and loss of control. One of the gears 10a of the gear train 50 10 is provided with a plurality of holes 11 accessible from the outside of a cover 12 enclosing

the gear train to permit insertion of a locking pin 13. The counterpoises may be swung manually, being provided with handles 14 for this purpose, and when properly adjusted so the beam 1 is horizontal, they may be locked in position by dropping the pin 13 into one of the holes 11 of the gear 10a. Other means of locking the counterpoises at any one of a number of different positions may be substituted for this arrangement, although the safety and foolproofness of the latter is an advantage.

The plate 2 connects with the beam 1 at the counterpoise end by way of a pin 15 which is dropped in undercut slots 16 formed in a vertical slot between the two arms 8, and there retained by reason of its other end being fastened between spaced ears 17 at the socket end of the beam by a pin 18 passed through these ears and a hole in the plate 2. This pin 18 is removably retained by means of screws 19, it being possible to remove 20 easily the plate 2 upon the removal of this pin 18 by moving the plate slightly toward the counterpoise end so as to unhook the pin 15 from the undercuts in the slots 16.

Although a specific example of the invention 25 has been disclosed in accordance with the patent statutes, it is not intended to limit its scope exactly to this example, except to the extent defined by the appended claims.

I claim:

1. A counterpoise arrangement for a rolling mill roll handling device of the type including a beam adapted to be suspended by a crane or the like and having a roll neck socket at one end, said arrangement comprising two counterpoises pivoted at the end of said beam opposite said socket to swing horizontally and a gear train interconnecting said counterpoises to cause them to swing in opposite directions in synchronism. 30

2. A counterpoise arrangement for a rolling mill roll handling device of the type including a beam adapted to be suspended by a crane or the like and having a roll neck socket at one end, said arrangement comprising two counterpoises pivoted at the end of said beam opposite said socket 35 to swing horizontally, a gear train interconnecting said counterpoises to cause them to swing in opposite directions in synchronism, and means for releasably locking said counterpoises immovable at different positions. 40

CARL E. MOORE. 50
